STUDY RULER

Herschell G. Martin, Philadelphia, Pa.

Application February 1, 1950, Serial No. 7,620

Term of patent 14 years

(Cl. D52—1)

To all whom it may concern:

Be it known that I, Herschell G. Martin, a citizen of the United States of America, residing at Philadelphia, county of Philadelphia, and State of Pennsylvania, have invented a new, original, and ornamental Design for a Study Ruler, of which the following is a specification, reference being had to the accompanying drawing, forming a part thereof wherein:

Figure 1 is a top plan view of a study ruler, showing my new design.

Figure 2 is a view in edge elevation of the ruler, and

Figure 3 is a perspective view of the ruler.

I claim:

The ornamental design for a study ruler, as shown.

HERSCHELL G. MARTIN.
